UNITED STATES PATENT OFFICE

AUGUST H. LEIPERT, OF COLLEGE POINT, NEW YORK, N. Y., ASSIGNOR TO INTERNATIONAL MOTOR COMPANY, OF NEW YORK, N. Y., A CORPORATION OF DELAWARE

VEHICLE FOR COLLECTING ASHES

Application filed April 4, 1930. Serial No. 441,486.

The present invention relates to vehicles of the commercial type and embodies, more specifically, an improved vehicle for collecting and transporting ashes and other refuse, the construction thereof being such that the substance to be loaded and transported is easily loaded and the body thereof being of such character that it may be loaded to its maximum content.

10 Existing vehicles designed for service of this character, in order to carry a sufficient quantity of refuse, are constructed with bodies which are comparatively large and therefore difficult to load. It is quite usual 15 therefore with existing designs to have a man on the body to supervise the loading, helping not only in the distribution of the load within the body but in the actual lifting of the containers which are to be dumped. 20 With a view to eliminating the personal required in service of this character, the present invention seeks to provide a body which is automatically loaded, the contents being lifted from a convenient location and 25 dumped into the body by a power operated mechanism. In this manner, the containers to be dumped need only be lifted to a relatively low height and dumped into a suitable receiving bin, the refuse so dumped being 30 automatically lifted and loaded within the body by means of a conveyor described hereinafter.

An object of the invention, accordingly, is 35 to provide a vehicle of the above character, the same being constructed in such manner that substance to be loaded therein need only be lifted to a moderate height, the capacity of the vehicle nevertheless being preserved at a maximum.

40 A further object of the invention is to provide a construction of the above character, a power driven conveyor being provided to lift the refuse to be transported from a convenient height to the top of the body in 45 order that the body may have a maximum capacity.

A further object of the invention is to provide a device of the above character by means of which the body may be loaded to 50 its maximum content.

Further objects, not specifically enumerated above, will be apparent as the invention is described in greater detail in connection with the accompanying drawings, wherein:

Figure 1 is a view in side elevation showing a vehicle constructed in accordance with the present invention and provided with a body having a preferred form of loading mechanism. 55

Figure 2 is a view in section, taken on line 60 2-2 of Figure 1, and looking in the direction of the arrows.

Figure 3 is a view in section, taken on line 65 3-3 of Figure 2, and looking in the direction of the arrows.

Referring to the above drawings, *a* designates the chassis of a vehicle which may be of any well known form. Upon this chassis a body *b* is mounted, the same preferably being hinged thereto at *a'*. A source of power, 70 which preferably is the engine of the vehicle, drives a power shaft *b'* for supplying power to a loading mechanism described hereinafter.

Although the body may take any desired form, it is shown as generally rectangular and 75 preferably constructed so that it is completely closed and comparatively airtight. A door *b* is preferably hinged thereon at *b*, as shown in Figure 1, this construction being such that the contents of the body may be 80 readily dumped when the door is unlatched and the body moved to the position shown in dot and dash lines in Figure 1.

At the forward extremity of the body an enlarged housing *c* is formed. This housing 85 is provided with a cylindrical drum *d* which is preferably mounted upon the front end plate of the enlarged housing *c* and secured within the body *b* by means of a supporting plate *d'*. In this manner, the end wall *c'* of 90 the enlarged housing *c* and the plate *d'* serve as a supporting means, not only for the drum *d*, but also for stub shafts *e* which are secured in the plates *c'* and *d'*. These stub shafts *e* are provided with rollers *e'* which support an 95 annular conveyor *f*.

This conveyor is formed of spaced annular parallel plates *f'*, the inner and outer peripheries of which are turned over as at *f* and *f*, respectively. Between the plates *f'*, lifting 100

buckets f^4 are secured, the form of these buckets being illustrated in Figure 2. The buckets f^4 thus serve not only as a lifting means but also as a bracing means for the 5 plates f' . Within the space formed by the flanges of the forward plate f' and secured to the inner flange f^2 is an annular geared track g which is engaged by a driving pinion g' , mounted upon shaft g^2 which is journaled 10 within the front plate c' . A bevel gear g^3 is secured to the shaft g^2 and is engaged by a cooperating pinion g^4 which is mounted upon power shaft b' . A housing g^5 serves to enclose the driving mechanism described above 15 and, in this manner, power from shaft b' is supplied to the annular conveyor in order to effect its rotation.

At a point on the enlarged portion c of the housing and adjacent the lower extremity 20 thereof, a bin h is provided, the lower surface h' of which is preferably sloped as shown in Figure 2. Trap door h^2 is hinged at h^3 in order that it may be opened readily and receive refuse which is to be loaded within the 25 vehicle. After the contents of a can or other receptacle is emptied into the bin h the conveyor is operated to cause the buckets f^4 to lift such contents until they reach an aperture d^2 which is formed within the cylindrical drum d . Upon reaching this aperture the 30 buckets begin to move into a dumping position, thus emptying the contents thereof into the cylindrical drum d . Continued loading, in this fashion, causes the substance loaded to 35 assume a position indicated generally by dot and dash lines in Figure 3. In order that the full capacity of the body may be utilized the body is moved to the dumping position shown in dot and dash lines in Figure 1, at 40 which time the contents slide rearwardly and clear the region about the drum d , thus enabling further loading to be effected. Any well known form of dumping mechanism may 45 be utilized and the connection of the power shaft b' may be such that it may be emptied effectively without impairing the power transmitting mechanism.

From the foregoing, it will be seen that a vehicle has been constructed, the capacity of 50 which is very great, at the same time, reducing the labor involved in loading refuse, etc., into the body. Since the body is closed and relatively airtight, offensive odors will not be present in the vicinity of the vehicle and this 55 objectionable characteristic to vehicles in service of this character is thus effectively overcome.

While the invention has been described with specific reference to the accompanying 60 drawings, it is not to be limited, save as defined in the appended claims.

I claim as my invention:

1. A vehicle having a dump body, a bin in the body adjacent the lower portion of the 65 same to receive material to be loaded, the bot-

tom of the bin sloping downwardly and inwardly, a trap door for the bin, an annular conveyor mounted rotatably in the body adjacent the inner extremity of the sloping bottom of the bin, a cylindrical drum in the conveyor having an open end adjacent the interior of the body and an aperture adjacent the upper portion thereof, and means to rotate the conveyor. 70

2. A vehicle having a dump body, a bin in the body adjacent the lower portion of the same to receive material to be loaded, the bottom of the bin sloping downwardly and inwardly, an annular conveyor mounted rotatably in the body adjacent the inner extremity of the sloping bottom of the bin, a cylindrical drum in the conveyor having an open end adjacent the interior of the body and an aperture adjacent the upper portion thereof, and means to rotate the conveyor. 75

3. A vehicle having a dump body, means on the body adjacent the lower portion of the same to receive material to be loaded, an annular conveyor mounted rotatably in the body adjacent the receiving means, a cylindrical drum in the conveyor having an open end adjacent the interior of the body and an aperture adjacent the upper portion thereof, and means to rotate the conveyor. 80

4. A vehicle having a body, means on the body adjacent the lower portion of the same to receive material to be loaded, an annular conveyor, means to mount the conveyor rotatably on the body adjacent the receiving means, a cylindrical drum within the conveyor having an aperture adjacent its upper extremity, a power shaft, gear teeth on the conveyor, and gearing between the shaft and teeth to rotate the conveyor. 85

5. A vehicle having a body, means on the body adjacent the lower portion of the same to receive material to be loaded, an annular conveyor, means to mount the conveyor rotatably on the body adjacent the receiving means, a cylindrical drum within the conveyor having an aperture adjacent its upper extremity, and means to rotate the conveyor. 90

6. A vehicle having a body, means on the body adjacent the lower portion of the same to receive material to be loaded, an annular conveyor, means to mount the conveyor rotatably on the body adjacent the receiving means, and means to rotate the conveyor, and an annular drum within the conveyor having an aperture adjacent its upper extremity and communicating with the body. 105

This specification signed this 31st day of March, A. D. 1930.

AUGUST H. LEIPERT.
